United States Patent Office.

EMANUEL YOUNG, OF AMANDA, OHIO.

Letters Patent No. 60,985, dated January 1, 1867.

IMPROVEMENT IN HOLLOW AUGERS.

The Schedule referred to in these Letters Patent and making part of the same.

TO ALL WHOM IT MAY CONCERN:

Be it known that I, EMANUEL YOUNG, of Amanda, Fairfield county, State of Ohio, have invented a new and useful Improvement in Auger for Fitting Spokes and Felloes; and I do hereby declare that the following is a full, clear, and exact description thereof, which will enable others skilled in the art to make and use the same, reference being had to the accompanying drawing, forming part of this specification, in which—

Figure 1 is a side view of my improved auger.

Figure 2 is an end view of the same.

Figure 3 is a longitudinal section of the same taken through the line *x x*, fig. 2.

Figure 4 is a cross-section of the same taken through the line *y y*, fig. 3.

Similar letters of reference indicate like parts.

My invention has for its object to furnish improved tools for fitting spokes and felloes together, so that they may fit each other exactly and in such a way as to give the greatest strength to that part of the tenon which is nearest the inner side of the felloes and upon which comes the greatest strain; and it consists, first, in an improved spoke-tenoning auger formed by combining an adjustable knife or cutter for forming the tapering sides of the tenon and two knives or cutters for forming the shoulder of the tenon with the hollow shank or body of the auger.

A is the shank, by means of which the auger is attached to the brace or other instrument for operating it. *B* is the body of the auger, the lower part of which is made hollow and the extreme lower part or end, *b*, tapering to correspond with the desired taper of the tenon. This lower part, *b*, is slotted longitudinally for the reception of the cutter *C*, and also to allow the chips to escape from the auger. *D* is a block attached to the side of the body, *B*, of the auger to assist in supporting the cutter *C*. The cutter *C* is attached to the edge of the said slot and to the side of the block *D* by two screws passing through slots in the said cutter and screwing into the said block *D*, so that the cutter *C* may be adjusted as required. The cutting edge of the knife, *C*, is made slightly flaring, so that it may make a cut a little wider than itself. Around the lower edge of the body *B* of the auger is formed a flange, *b'*, to support the cutters *E* which form the shoulder of the tenon of the spokes. These cutters *E* are set a little inclined, so that their edges, *e'*, may slightly project to take hold of and operate upon the spoke being tenoned. The chips made by the cutters *E* escape through the notches or slots *b'* formed beneath the cutting edges of the said knives *E*. These cutters are attached to the body of the auger by screws, two to each, as shown in fig. 2. By the use of this instrument the tenon is made strongest at the inner edge of the felloes, at which point the spokes are more liable to break than at any other.

Having thus described my invention, what I claim as new, and desire to secure by Letters Patent, is—

As an article of manufacture, the hereinbefore-described tool formed with the knives *C* and *E* attached to the hollow tapering body *B*, formed with the shank *A*, for attaching the tool to a brace, substantially as described.

The above specification of my invention signed by me this   day of   , 1866.

EMANUEL YOUNG.
